PRECISION VARIABLE FREQUENCY
GENERATOR

Arthur F. Naylor, Cleveland, Ohio, assignor to Thompson
Ramo Wooldridge Inc., a corporation of Ohio
Filed Dec. 23, 1957, Ser. No. 704,372
13 Claims. (Cl. 331—38)

This invention relates to a precision variable frequency generator.

It is an object of the invention to provide a precision variable frequency generator whose error is of essentially constant magnitude, rather than a constant percentage, over a relatively wide frequency range.

Another object of the invention is to provide a variable frequency generator having a high degree of stability and accuracy, a wide frequency range and automatic tuning.

A further object of the invention is to provide a relatively simple variable frequency generator utilizing a minimum number of oscillators, mixers, and tuned circuits, and imposing only modest limits on individual circuit stability or selectivity.

Still another object of the invention is to provide a variable frequency generator affording convenient and efficient frequency selection.

A more specific object of the invention is to provide a novel binary control system for a precision variable frequency generator.

A further more specific object of the invention is to provide a variable frequency generator utilizing a special limited-doublet binary system for limiting the range over which components must operate and accommodating a minimum of switching control equipment.

Another and further object of the invention is to provide a variable frequency generator which eliminates spurious frequencies in its output.

It is also an object of the invention to provide an extremely rugged and dependable precision variable frequency generator.

More specifically, it is an object to provide a precision variable frequency generator having a range of the order of from 1 to 1537 megacycles per second with a resolution of 10 kilocycles per second and a stability of about plus or minus 25 kilocycles per second over its entire frequency spectrum.

Other and further important objects, features and advantages of the present invention will be apparent from the following detailed description taken in connection with the accompanying drawings, in which:

FIGURE 1 is a block diagram of a precision variable frequency generator in accordance with the present invention;

FIGURE 2 is a block diagram of certain components of the generator of FIGURE 1; and

FIGURE 3 is a block diagram of the logical circuits for controlling switching in the generator of FIGURE 1.

As shown on the drawings:

Referring to FIGURE 1, it will be observed that the variable frequency generator in accordance with the illustrated embodiment may comprise a control panel 10 having knobs 11, 12 and 13 for manual actuation to control the apparatus. The panel may also be provided with a visual frequency indicator generally indicated at 15 which will represent the frequency being delivered by the generator. In FIGURE 1, the frequency 1352.73 megacycles per second is indicated.

The knob 11 controls a four position switch. In "Off" position, the primary supply voltage is disconnected from the generator; in "Standby" position, the filament circuits and crystal ovens are energized; in "Carrier Off"

2

position, all internal functions of the equipment are activated except for the output selector switch; and in "Carrier On" position, the output selector switch is energized to connect the generator to the output cable.

5 The inner knob 12 may be termed a vernier frequency control and is suitably coupled to a motor 16 driving a shaft 17 which is coupled to a variable frequency oscillator 18 for tuning the oscillator between 1 and 2 megacycles per second. The variable frequency oscillator 18 is preferably temperature compensated for stability of the order of plus or minus 10,000 cycles per second. The variable frequency oscillator is also preferably ruggedized to insure dependable operation. The dial calibration is preferably approximately linear over the required range of from 1 to 2 megacycles per second. The motor shaft 17 is coupled to a digital counter 20 by means of gears 22 and 23 and the digital counter 20 controls the last two positions of indicator 15 to the right of the decimal point. In the illustrated embodiment shaft 17 is at an angular position corresponding to a frequency of 1.73 megacycles per second for variable frequency oscillator 18. The frequency indicator is set to include the one megacycle per second contributed by variable frequency oscillator 18. The coupling between vernier control 12 and motor 16 is indicated by line 25.

10 The knob 13 on the control panel in the illustrated embodiment controls the coarse frequency adjustment as represented by the four digit positions to the left of the decimal point of frequency indicator 15. In the central position of the knob 13 indicated, the frequency of the generator remains that indicated by indicator 15, namely 1352 megacycles per second. If knob 13 is moved in the clockwise direction, the frequency is increased toward maximum frequency, and the rate at which the frequency is increased is controlled by the angular position of knob 13. Thus, positions 28, 29 and 30 correspond to slow, medium and fast increases in frequency, while positions 32, 33 and 34 counterclockwise from central position 35 correspond to slow, medium and fast reduction of the frequency delivered by the generator. In FIGURE 1, knob 13 is illustrated as being coupled to a transfer switch 40 by means of a line 41. The transfer switch 40 connects 5 cycle per second oscillator 43, 50 cycle per second oscillator 44 or 500 cycle per second oscillator 45 to binary decimal register 50 depending on whether a slow, medium or fast rate of change of frequency is desired. Line 52 may represent the connection of one of the oscillators 43, 44 or 45 through transfer switch 40 with 50 binary decimal register 50 while line 53 may represent the control for determining whether register 50 adds or subtracts depending on whether the knob 13 is moved clockwise or counterclockwise from its central position 35. The information from the binary decimal register 50 controls electronic decimal numbering indicator 15 to the nearest megacycle as indicated by line 56.

15 The information in the binary decimal register 50 is sent to a transfer register 60 and then, in natural binary code, to binary register 61. In the illustrated embodiment, the number 1351 would have been sent to the binary register 61 to require that the fixed frequency system generate a frequency of 1351 megacycles per second. The variable frequency oscillator 18 adds to this 1.73 megacycles per second to generate the frequency represented on the frequency indicator 15 in FIGURE 1.

20 A fixed frequency oscillator bank indicated at 65 comprises a series of fixed oscillators each of twice the frequency of the preceding oscillator. In the illustrated embodiment, the bank 65 may comprise ten fixed frequency oscillators 67 to 76 having frequencies of 1 megacycle per second, 2 megacycles per second, 4 megacycle per

second, 8 megacycles per second, 16 megacycles per second, 32 megacycles per second, 64 megacycles per second, 128 megacycles per second, 256 megacycles per second and 512 megacycles per second as represented in FIGURE 2.

The outputs from the fixed frequency oscillators of bank 65 are suitably combined by means of mixers 80—90 shown in FIGURE 2 and arranged in two banks 93 and 94 as illustrated in FIGURE 1. The outputs of the fixed frequency oscillators 67—76 are suitably combined under the control of two sets of switch arms 100—107 and 110—118 as represented by blocks 122 and 123 in FIGURE 1. The outputs of the respective mixers 80—90 are connected to amplifiers 126—136 indicated as being arranged in two banks 140 and 141 in FIGURE 1. A series of selector switch arms 150, 151, 152 and 153 are positioned to connect the desired amplifier 126—136 to output cable 155, FIGURE 2, and the selector switches are represented by block 157 in FIGURE 1.

The ten fixed frequency oscillators 67—76 in FIGURE 2 may operate at successive fixed frequencies in the range between 1 and 512 megacycles per second to provide frequencies at the output cable 155 anywhere in the range between 1 and 1537 megacycles per second in conformity with the embodiment illustrated in FIGURE 1 where frequency indicator 15 has been stated to be calibrated in megacycles per second. While operation in this frequency range is at present considered to be most significant, the circuit of FIGURES 1, 2 and 3 is, of course, directly applicable to any desired frequency range. For example, if output frequencies in the range from 1 to 1537 kilocycles per second were desired, oscillators 67 to 76 would provide successive frequencies in the range between 1 kilocycle and 512 kilocycles per second, and variable frequency oscillator 18 would provide frequencies between 1 and 2 kilocycles per second. Accordingly, there is no intention to limit the disclosure of FIGURES 1, 2 and 3 to the megacycle range, and the number designations within the circles representing oscillators 67 to 76 and within the blocks representing amplifiers 126—136 in FIGURE 2 are intended simply to represent relative values and might in an actual circuit represent kilocycles, tens of kilocycles, hundreds of kilocycles, megacycles or any other suitable units. The circuits of FIGURES 1, 2 and 3 thus have utility in other frequency ranges than the megacycle range which is a preferred example, and the drawings are specifically intended to illustrate the other of frequency ranges referred to herein.

In the case where the circuits of FIGURES 1, 2 and 3 are taken to represent the megacycle range, oscillators 67 to 76 are preferably crystal controlled. The higher frequencies are preferably derived from one fixed frequency by doubling and quadrupling through selective tank circuits tuned to the desired frequency such as 512 megacycles per second for oscillator 76. In the present state of the art, it is practical to use frequency doubling up to 2000 megacycles per second with efficiency and output sufficient for the present embodiment of the invention. The mixers or frequency adders 80—90 preferably operate by known heterodyning techniques. With the illustrated circuits, the mixer stages 80—85 which operate up to a frequency of 65 megacycles per second are preferably conventional grid-cathode mixers with untuned plate circuits. For mixers 86—90 handling frequencies above 65 megacycles per second, the tank circuit of the mixer will be tunable over the spectrum of frequencies indicated for the associated amplifiers 132—136. As illustrated in FIGURE 1 by line 170, continuous tuning information is derived from the binary register 61 and supplied to an automatic mixer tuning control indicated at 171 to control the tuning of mixers 86—90 in tuner bank 94. The tunable tank circuits of the mixers 86—90 preferably have a reasonable "Q" so as to realize gain and selectivity. Preferably also, the mixer subassemblies are miniaturized

plug-in packages to enable quick replacement in case of failure.

In the case where the amplifiers 126—136 are to operate in the megacycle range, amplifiers 126—133 utilize 5 distributed amplifier technique. Gains in excess of 10 db have been achieved with band widths to 200 megacycles per second. Amplifiers 134—136 employ modified broad banding techniques approaching a tunable radio frequency amplifier, preferably with a reasonable 10 "Q" so as to realize gain and selectivity. As represented by line 170 and block 171 in FIGURE 1, tuning of amplifiers 134—136 in bank 141 is controlled by means of 15 binary register 61 with actual tuning accomplished through the use of binary autopositioners or through voltage tuned devices properly excited by an analog voltage derived from the binary register 61. The amplifiers are preferably 20 designed in modular form for ease of replacement in case of failure, and are preferably designed for the utmost in maintainability and reliability.

The switches 100—107 and 110—118 in the radio frequency range may be two position coaxial switches having 25 solenoid actuating mechanisms which are energized under the control of binary register 61 by means of a power transistor bank indicated at 175 in FIGURE 1.

Output switches represented at A, B, C and D in FIGURE 2 having arms 150—153 may comprise four position coaxial switches and are controlled from the binary register 61 as indicated by line 177 in FIGURE 1. These 30 switches preferably provide the maximum practical isolation and reduction of crosstalk between channels. The operation of the output selector switches A, B, C and D in FIGURE 2 involves the use of the frequency as given in the binary register 61 for connecting the output cable 155 to the proper amplifier 126—136. The output switches 35 in conjunction with the other two sets of switches contribute to the elimination of spurious frequencies at the output cable 155.

In selecting a desired frequency in the illustrated embodiment, the operator adjusts coarse frequency control 40 knob 13 so as to cause binary-decimal register 50 to count in a desired direction at the desired rate, without any readout from the binary-decimal register 50 to the transfer register 60. Binary-decimal register 50 simply counts up or down until a desired frequency appears at 45 the indicator 15. The operator then moves the control knob 13 to central position 35 to set the register 50 at the count corresponding to the desired frequency. Vernier control knob 12 is actuated to set variable frequency oscillator 18 at a frequency to provide the desired decimal fraction at indicator 15. When control knob 13 has 50 been set back to central position 35, readout from register 50 is initiated to adjust the various components so as to deliver the selected frequency.

It will be apparent that the present invention also comprehends the embodiment wherein variable frequency oscillator 18 is omitted or replaced by a fixed frequency oscillator such as of 1 megacycle and the system is utilized to generate frequencies over a given range in unit steps. It is considered that the diagram of FIGURE 2 55 comprehends the embodiment of a fixed oscillator in place of variable frequency oscillator 18, since this embodiment is achieved by simply setting variable frequency oscillator 18 at 1 megacycle per second, for example.

Certain details of the binary register and logic component indicated at 61 in FIGURE 1 are shown in FIGURE 3. The circuitry of FIGURE 3 provides means for controlling actuation of switches 100—107 and 110—118 60 so as to produce a frequency at output cable 155 corresponding to the number counted into register 50 in FIGURE 1. Thus, blocks 200—207 in FIGURE 3 represent control circuits for the respective power transistor amplifier units of bank 175 in FIGURE 1 which in turn control the switch arms 100—107 in FIGURE 2. Similarly 65 blocks 210—218 in FIGURE 3 represent control circuits for the respective power transistor amplifier units of bank 70

175 which control switch arms 110—118 in FIGURE 2.

The input from the transfer register 60 in FIGURE 1 is represented by the line 220 leading to a series of binary register units 221—231 corresponding to code positions 1—1024 in the binary code. It will be understood that the number recorded in the transfer register 60 may be delivered to units 221—231 in parallel so that the condition of each code position in register 60 is transmitted directly to the corresponding binary register unit 221—231 of FIGURE 3 under the control of a corresponding gate, for example.

For example if the number 1351 is delivered to register units 221—231 to correspond to the frequency represented on indicator 15 in FIGURE 1 (taking into account a setting of 1.73 of variable frequency oscillator 18) this number is represented in the binary code reading the most significant code position first as 10101000111. When this number is fed to register units 221—231, units 221, 222 and 223 will be in their "1" condition, units 224, 225 and 226 will be in their "0" condition, units 227, 229 and 231 will be in their "1" condition, and units 228 and 230 will be in their "0" condition.

The control circuits 200—207 and 210—218 are actuated by the respective register units under the control of "and" gates 240—247 and "inhibitor" gates 250—257. The "and" gates 240—247 are each actuated by a "0" condition of two successive register units. The inhibitor gates 250—257 are each inhibited upon actuation of the associated "and" gate, but otherwise transmit an actuating signal to the associated control circuit 211—218 upon a "0" condition of the associated register unit. The control circuits 200—207 are actuated upon actuation of the associated "and" gate. In deactuated condition of control circuits 200—207 and 210—218, the associated switch arms are in their positions shown in FIGURE 2 which are designated their direct or "D" positions. When the control circuits are actuated due to "0" conditions in the associated register units, the corresponding switches are moved to their offset or "0" positions. Thus for the number 1351 in the registers 221—231, register unit 224 will be in "0" condition to actuate control unit 213 through lines 270 and 271 and inhibitor gate 252. Inhibitor line 273 of inhibitor gate 252 is not actuated since "and" gate 242 remains deactuated because of the "1" condition of register 223.

Since both register units 224 and 225 are in an "0" condition, "and" gate 243 is actuated to actuate control unit 203 and place inhibitor gate 253 in blocking condition through inhibitor line 277. Thus the zero condition of unit 225 fails to actuate control unit 214. Similarly, control unit 204 is actuated and control unit 215 is not actuated. The "0" condition of unit 228 causes actuation of control unit 217.

With this condition of the logic circuitry associated with the binary register, switch arms 103 and 104 are actuated and switch arms 113 and 117 are actuated. If variable frequency oscillator 18 is set to 1.73 megacycles to correspond with indicator 15 in FIG. 1, the first mixer 80 will receive a 1 megacycle frequency from oscillator 67 at a first input and will receive a frequency of 1.73 megacycles at a second input to provide an output of 2.73 megacycles to amplifier 126. The output of amplifier 126 is connected by switch 110 in its direct position to one input of mixer 81 to provide an output of 4.73 megacycles to the second amplifier 127. The output of the amplifier 127 is delivered to mixer 82 which generates an output of 8.73 megacycles for amplifier 128. Since switch arm 113 is in its offset position, the output of amplifier 128 is connected to an input of mixer 84 to provide an output of 24.73 megacycles to amplifier 130. Since switch arm 103 is actuated to its offset position, mixer 85 receives a first input of 16 megacycles and an input from amplifier 130 of 24.73 megacycles to provide an output of 40.73 megacycles. With switch arm 104 in its offset position, mixer 86 receives an input fre-

quency of 32 megacycles to provide an output of 72.73 megacycles. With switch arm 117 in its offset position, the output of amplifier 132 is connected to the input of mixer 88 to provide an output of 328.73 megacycles per second. At mixer 89, 512 megacycles is added to this value and at mixer 90 a further 512 megacycles per second is added to provide the total of 1352.73 megacycles per second represented on indicator 15 in FIGURE 1.

It will be observed that the circuits of FIGURES 2 and 3 do not operate on what may be termed a simple binary basis. On a simple basis, for the number 1351, fixed oscillators of frequencies of 1, 2, 4, 64, 256 and 1024 megacycles per second would be added in correspondence with the presence of "1" signals in the 1, 2, 4, 64, 256 and 1024 code positions in the binary code representation of the number 1351. Referring to the circuit of FIGURE 2, this would require a further position on each of switches 111—118, for example, in order to connect mixers 82—89 to the output of the variable frequency oscillator 18. A further contact would be required in conjunction with switch arm 112, for example, in order to connect mixer 83 directly to the output of amplifier 126. Each succeeding switch arm 113—118 would require progressively greater numbers of contacts so that each mixer second input could be connected directly to the output of any of the preceding mixer stages. It will be appreciated that this arrangement (not shown) is far more complex than the one actually illustrated in FIGURE 2.

The circuits of FIGURES 2 and 3 operate on a modified binary code which may be termed a special limited-doublet binary numbering system. Thus, referring to the number 1351 in its binary form and reading from the least significant binary position, it will be observed that the 0 in the eight position produces the normal action of excluding oscillator 70 in FIGURE 2 by actuation of switch arm 113 to offset position. The second zero at the sixteen position, however, does not produce the normal action, but instead causes actuation of switch arm 103. Thus, the sixteen megacycles from oscillator 71 is added both at mixer 84 and at mixer 85. Similarly because of the "second" zero at the thirty-two position, oscillator 72 is connected to mixer 86 and oscillator 73 which provides the 64 megacycles is disconnected. Thus, instead of connecting the output of mixer 82 directly to mixer 86, a chain is established for providing 16 megacycle signals at mixers 84 and 85 and a 32 megacycle signal at mixer 86. The sum 16+16+32 is of course equal to 64 megacycles per second. Thus, a continuous chain is preserved from the output of mixer 82 through switch arm 113 in offset position and mixers, 85 and 86, while still providing the required 64 megacycle per second frequency.

It will be apparent to those skilled in the art that the output switches A, B, C and D may also be controlled from the storage register units 221—231. Thus with all the register units in their zero condition, switch A must have arm 150 in the number 1 position and switch D must have arm 153 in its number 1 position. If the first register unit 221 has a one condition and all the other registers are zero, switch A must be in position two. If register unit 222 is in a one condition and all subsequent units 223—231 are in a zero condition, switch A must be in position number 3 regardless of the condition of register unit 221. This will be understood by referring to the ranges for which amplifiers 126—136 are adapted.

If register unit 222 is in a one condition the binary number is either 2 or 3 which when added to the output of the variable frequency oscillator 18 falls within the range of amplifier 127. If the unit 223 is the highest unit in a one condition, the binary number is equal to or less than seven, and switch A must be in position four at the output of amplifier 128. Thus, the rule for the positioning of switches A, B and C is that switch A must be in a position corresponding to the highest register unit

of units 221, 222 and 223 in a one condition. If none of units 221, 222 and 223 is in a one condition, switch A must be in its number 1 position; for switch B the position must correspond to the highest register unit of units 224—227 in a one condition; for switch C, the position must correspond to the highest unit of units 228—231 in a one condition. With respect to switch D, the position must number 1 if the highest register unit of units 221—231 in a one condition is 221, 222 or 223 or none of the units; switch D must be in position two if one of units 224—227 is the highest unit in a one condition; and switch D must be in its number 3 position if one of units 228—231 is the highest unit in one condition.

It will thus be seen that with simple logical circuitry such as illustrated in FIGURES 2 and 3, a single binary number input is operative to control switches 100—107, switches 110—118 and switches A—D. Such circuitry alone is operative to provide output frequencies between 1 and 1537 units, where the frequency band is not such as to require tuning of the mixers such as bank 94 in FIGURE 1 and of the amplifiers such as those in bank 141 in FIGURE 1. With additional circuitry such as indicated in FIGURE 1, the embodiment of FIGURES 1 to 3 is operative in the megacycle range to automatically provide an output between 1 and 1537 megacycles, for example. Switches A, B, C and D may, of course, be actuated manually if desired in a given application, and the disclosure in FIGURES 2 and 3 is intended to include this embodiment.

Summary

In a preferred form of operation of the generator of FIGURES 1 to 3, the generator is utilized to provide any frequency within a predetermined range to output cable 155 in FIGURE 2. If it is desired, for example, to tune the generator to a frequency of 521.40 megacycles per second, knob 13 is turned counterclockwise to one of positions 32, 33 or 34 to cause one of oscillators 43, 44 or 45 to deliver pulses via line 52 to register 50. The register 50 will then count down at the selected rate. When the number 521 appears at indicator 15, knob 13 is moved to central position 35 to set the register 50 at the corresponding binary-decimal number. Vernier knob 12 may be moved counterclockwise causing rotation of shaft 17 of motor 16 and corresponding actuation of digital counter 20 until the number .40 appears to the right of the decimal point at indicator 15. The knob 12 is returned to its center position and shaft 17 will have tuned variable frequency oscillator to a frequency of 1.40 megacycles per second.

With the binary-decimal number corresponding to the desired frequency in register 50, register 50 is suitably actuated to deliver the binary-decimal number to transfer register 60 from whence it is delivered to the binary register and logic circuit 61 shown in detail in FIGURE 3. Register units 221—231 of binary register and logic circuit 61 are thus set in conditions corresponding to one less than the number transferred from register 50. For a binary number of 520, units 224 and 230 would be in a one condition, while the remaining units would be in a zero condition energizing lines 300—307. Actuating unit 210 would be energized to move switch arm 110 in FIGURE 2 to offset position bypassing mixer 80. "And" circuit 240 will be energized to deliver an inhibiting pulse via line 310 to prevent actuation of actuating circuit 211. "And" circuit 240 will also actuate actuating circuit 200 to move switch arm 100 to offset position connecting fixed oscillator 68 to the first input of mixer 82. "And" circuit 241 will also be energized preventing actuation of circuit 212 and energizing circuit 201 to move switch arm 101 to offset position in FIGURE 2 connecting oscillator 69 to the input of mixer 83. "And" circuit 242 is not energized nor is "and" circuit 243 because of the one condition of register unit 224. The zero condition of unit 225 will thus be transmitted by lines 303 and 312 and in-

hibitor gate 253 to actuating circuit 214 to cause switch arm 114 in FIGURE 2 to be moved to offset position. "And" circuits 244—247 will be energized because of the zero condition of units 225—229 of storage register 61, and this will cause the actuation of circuits 204—207 to actuate switch arms 104—107 in FIGURE 2.

With the logical circuits of FIGURE 3, it will be observed that instead of hooking oscillators 70 and 76 to a mixer to produce 520 megacycles by simple analogy with the binary code representation of the number 520, a chain of fixed oscillators is established providing two megacycles at mixer 81, two megacycles at mixer 82 and four megacycles at mixer 83 to correspond to the required eight megacycles. Mixer 84 is excluded from the chain by actuation by switch arm 114 to offset position, and 32 megacycles is supplied to mixer 85 and to mixer 86, sixty-four megacycles is supplied to mixer 87, 128 megacycles is supplied to mixer 88 and 256 megacycles is supplied to mixer 89 to provide the total of 512 megacycles per second.

By preserving a continuous chain of mixers in this manner, switching is greatly simplified, and the band width requirements for amplifiers 126—136 is greatly improved.

Selector switch arms 150—153 are properly positioned so that only the desired amplifier is connected to output cable 155. In the present instance where an output of 520+1.40 megacycles is desired, switch arm 152 is at position 3 connecting with amplifier 135, and switch arm 153 is in position 3. Thus, the outputs of the other amplifiers are effectively excluded from output cable 155.

It will be apparent that many modifications and variations may be effected without departing from the scope of the novel concepts of the present invention.

I claim as my invention:

1. In combination, a series of frequency sources providing successive different output frequencies, a series of frequency adders each having first and second inputs and an output, means for connecting each frequency source to the first input of a respective one of said adders and to the first input of the adder following said one of said adders in said series of adders, and means for connecting the output of each adder to the second input of the next succeeding adder.

2. In combination, a series of frequency sources providing successively different output frequencies, a series of frequency adders each having first and second inputs and an output, means for connecting each frequency source to the first input of one of said adders, and means for selectively connecting the output of each adder with the second input of the next succeeding adder and to the second input of the adder following the next succeeding adder in said series of adders.

3. In combination, a series of frequency sources providing successively different output frequencies, a series of frequency adders each having first and second inputs and an output, means for selectively connecting each frequency source to the first input of one of said frequency adders and to the first input of another of said frequency adders next succeeding said one frequency adder in said series of adders, and means for selectively connecting the output of each adder to the second input of the next succeeding adder in said series of adders and to the second input of the adder after the next succeeding adder.

4. In combination, a series of frequency sources providing successively different output frequencies, a series of frequency mixers each having first and second inputs and an output, means for selectively connecting each frequency source to the first input of one of said mixers and to the first input of another of said mixers next succeeding said one of said mixers in said series of mixers, means for connecting the output of each mixer selectively to the second input of the next succeeding mixer in said series of mixers and to the second input of the mixer after said next succeeding mixer, output means for receiving an out-

put frequency, and selector switch means for selectively connecting said output means with the output of each of said mixers.

5. In combination, a series of frequency sources providing successively different output frequencies corresponding to successive powers of two, a series of frequency adders each having first and second inputs and an output, means for connecting each frequency source to the first input of a respective one of said adders and to the first input of the adder following said one of said adders in said series of adders, means for connecting the output of each adder to the second input of the next succeeding adder in said series of adders, a series of wide band amplifiers each connected to the output of one of said adders and covering a frequency range including the sum of the output frequency of the frequency source connected to the first input of said one of said adders and the output frequencies of all frequency sources preceding said frequency source connected to said one of said adders.

6. In combination, a series of frequency sources providing successively different output frequencies, a series of frequency adders each having first and second inputs and an output, means for selectively connecting each frequency source to the first input of one of said frequency adders and to the first input of another of said frequency adders next succeeding said one of said adders in said series of adders, means for connecting the output of each adder selectively to the second input of the next succeeding adder in said series of adders and to the second input of the adder following said next succeeding adder, output means for delivering an output frequency, and selector switch means for selectively connecting said output means with the output of each of said adders.

7. In combination, a series of frequency sources each providing an output frequency twice the output frequency of the preceding frequency source in said series, a series of frequency adders each having first and second inputs and an output, means for selectively connecting each frequency source to the first input of one of said frequency adders and to the first input of another of said frequency adders next succeeding said one of said frequency adders in said series of adders, means for connecting the output of each adder selectively to the second input of the next succeeding adder in said series of adders and to the second input of the adder following said next succeeding adder, and a series of amplifiers each connected to the output of one of said adders and covering a frequency range including a frequency equal to the sum of the output frequency of the frequency source connected to the first input of said one of said adders and the output frequencies of all frequency sources preceding said frequency source connected to said one of said adders.

8. In combination, a series of frequency sources providing successively different output frequencies, a series of frequency mixers each having first and second inputs and an output, means for connecting each frequency source to the first input of a respective one of said mixers and for connecting each frequency source to the first input of the mixer following said one of said mixers, means for connecting the output of each mixer to the second input of the next succeeding mixer, and a variable frequency source connected to the second input of the first mixer of said series.

9. In combination, a series of frequency sources each providing an output frequency twice the output frequency of the preceding frequency source, a series of frequency adders each having first and second inputs and

an output, means for selectively connecting each frequency source to the first input of one of said frequency adders and to the first input of another of said frequency adders next succeeding said one of said frequency adders in said series of adders, and means for connecting the output of each adder selectively to the second input of the next succeeding adder in said series of adders and to the second input of the adder following said next succeeding adder in said series of adders.

10. In combination, a series of frequency sources each providing an output frequency twice the output frequency of the preceding source in said series, a series of frequency adders each having first and second inputs and an output, means for connecting each frequency source to the first input of one of said adders, means for connecting the output of each adder to the second input of the next succeeding adder, and a variable frequency oscillator covering the range of frequencies between the output frequencies of the first and second frequency sources of said series of frequency sources connected to the second input of the first adder of said series of adders.

11. In combination, a series of frequency sources each providing an output frequency of twice the output frequency of the preceding frequency source, a series of frequency adders each having first and second inputs and an output, means for selectively connecting each frequency source to the first input of one of said frequency adders and to the first input of another of said frequency adders next succeeding said one of said frequency adders in said series of adders, means for connecting the output of each adder selectively to the second input of the next succeeding adder in said series of adders and to the second input of the adder following said next succeeding adder, a variable frequency oscillator connected to the second input of a first one of said series of adders, output means for delivering an output frequency, and selector switch means for selectively connecting the output of each adder with said output means.

12. In combination, a series of frequency sources providing successively different output frequencies, means for mixing the output frequencies of at least two successive frequency sources of said series of frequency sources to provide a resultant output frequency, and means for mixing said resultant output frequency selectively with the output frequency of the succeeding frequency source next following said two successive frequency sources in said series of frequency sources and with the output frequency of the one of said two successive frequency sources preceding said succeeding frequency source in said series of frequency sources.

13. In combination, a series of frequency sources providing respective output frequencies corresponding to successive powers of two, means for mixing the output frequencies of at least first and second ones of said series of frequency sources to provide a resultant output frequency, and means for mixing said resultant output frequency selectively with the output frequency of a third one of said series of frequency sources and with the output frequency of one of said first and second frequency sources.
